UNITED STATES PATENT OFFICE

GRANVILLE E. PALMER, OF BROOKLINE, MASSACHUSETTS, ASSIGNOR, BY MESNE ASSIGNMENTS, TO THE PALMER ELECTRIC & MANUFACTURING CO., OF WALTHAM, MASSACHUSETTS, A CORPORATION OF MASSACHUSETTS

METER INSTALLATION

Application filed July 3, 1924. Serial No. 724,028.

Electric meters, in service installations, have commonly been mounted on substantially vertical wooden boards or panels, which have also been employed to carry electrical service connections such as the switch and fuse mechanisms commonly associated with the meters. To render such installations as safe as possible as well as to prevent theft of current or unauthorized access to live conductors, the switch and fuses are often enclosed in protective metal casings having openings constructed to register with the meter terminal housings. It is also commonly required that the wooden boards or panels shall be painted with a fireproof paint.

This invention provides a construction in which the necessity of a wooden board or panel is eliminated, and by means of a construction by which the housing for the switch and meter protecting devices is made use of in connection with a metal plate or board for supporting the meter, in a manner which permits the casing to form part of the mounting means. This is done by attaching to the vertical rear face of the casing a plate to which the meter may be fixed, and fixing to the upper end of this plate and to the lower portion of the casing supporting feet, certain of which are adjustable in length. By this construction the assembled mechanism may be supported from any suitable wall in position so that the meter may be brought into a vertical plane.

This construction renders it easy to ground the metallic meter frame, this being accomplished in the present instance by merely grounding the casing or plate. By making the plate detachable from the casing and the plate and feet detached from the casing the plates are readily packed for shipment.

For a more complete understanding of this invention reference may be had to the accompanying drawings in which

Figure 1 is a front elevation of the casing for the meter protective devices and the meter support, the position of the meter being indicated in dotted lines.

Figure 2 is a side elevation of the same

showing the meter support and casing fixed to a wall.

Figure 3 is a detail plan partly broken away showing the wall attachment of the meter support. 55

Figure 4 is a fragmentary side elevation of the same.

Figure 5 is a perspective of the meter support and its wall attaching foot. 60

Figure 6 is a perspective of a foot for supporting the casing from a wall.

Figure 7 is a detail section on line 7—7 of Figure 5.

Referring to the drawings, 1 indicates a metallic box or casing of any suitable or usual construction for containing the switch and meter fuses or other meter protective devices. As shown this casing is provided with a hinged closure 2 covering a portion of its front face behind which the fuses are intended to be positioned. When the switch is in its "off" position, the closure is unlocked so that it may be opened and access obtained to the fuses. When the switch is in its "on" position the closure is locked in closed position. Any other type of casing might be used, however. On the back face of the casing 1 are shown attached a pair of feet, one being shown detached in Figure 6 as at 5. 65 As shown these feet are bent from bar stock in substantially Z shape, one end flange 6 being perforated for attachment to the casing 1, the opposite end or flange 7 being shown as provided with an angularly disposed slot 8 through which bolts or screws 70 may be passed into the supporting wall, as shown at 10 in Figure 2. These slots are formed so that the casing and the meter carried therewith, as will be later described, may be moved laterally at its lower end in order to adjust the meter into proper vertical position. 75

Attached to the upper portion of the casing 1 is shown the meter-carrying plate 15. 80 This meter-carrying plate is preferably provided with marginal rearwardly directed strengthening flanges 16 and is provided at its lower portion with perforations 17 through which attaching devices may be 85 passed to fix it firmly to the upper rear verti- 90 95 100

cal face of the casing 1. The upper end of the board or plate 15 is bent rearwardly, as shown at 18, and perforated at 19 for the reception of fastening bolts or screws 20 which also 5 pass through slots 21 in one flange of an angle foot member 22. The opposite flange of this member 22 at 23 is provided with an elongated slot 24 through which a suitable fastening device may be passed to fix this 10 angle foot to the wall 10. This slot also permits the upper end of the unit comprising the casing and the plate 15 to be adjusted so that the meter 30 carried by the plate 15 may be placed in its proper position.

15 The plate 15 may be provided with variously arranged slots 31 shaped to cooperate with various types of meters having their attaching bolts or screws positioned in different places. Such meters are usually fixed 20 by two screws or bolts adjacent their lower ends and a single one at their upper ends. To provide for this single fastener at the upper ends of various meters, a slot 32 is cut in the plate 15 adjacent to the opposite end 25 of the plate to receive this member and in order that this member may have a proper bearing on the plate 15 a strip 33 may be retained against the rear face of the plate by an integral loop 34 bent therefrom as shown 30 in Figures 5 and 7. This strip 33 is adjustable vertically on the rear face of the panel plate 15 and may have a meter fastener passed rearwardly through the slot 32 as at 35 engaged therewith, this strip bridging the slot 32. The strip 33 is prevented from turning by its engagement through the loop 34 so that when a threaded meter fastening element, as shown in dotted lines in Figure 2, is threaded thereinto no access to the rear 40 face of the plate is necessary in order to tighten the fastening. Furthermore, it extends always directly forwardly so that it is an easy matter to engage the meter therewith. When a meter is to be fixed in position the workman inserts a headed fastener into the strip 33, its head extending forwardly through the slot 32, the strip being then in its lowest position. He then takes the 45 meter with both hands, as it must be handled carefully, and finding that the fastener in the strip 33 is nearer to the casing top wall than the height of the meter, he tilts the meter laterally until he can engage the usual loop at the top of the meter over the fastener, the 50 absence of obstructions on the front face of the plate 15 permitting this. He then swings the meter to a vertical position, this acting to raise the strip 33, raising the meter sufficiently to clear the top wall of the casing 55 and then lowering it into proper position. He then moves the upper fastener to its upper limit as permitted by the meter loop and tightens it in position. The fastenings for the lower portion of the meter are then inserted and tightened. The loop 34 holds the 60 strip 33 against the rear face of the plate 15 quite independently of the meter fastening element, a suitable stop 36 thereon limiting the downward movement of the strip 33 by engagement with the lower end of the slot 32. When the upper fastening is tightened up the strip 33 is pulled against the rear face of the plate 15 and is held firmly in position. The meter is thus held firmly in position with its terminal housing registering with the upper end of the casing 1 which is supplied with an adapter plate of suitable form to close the space between the meter terminal housing and the adjacent casing walls to prevent access to the interior of the casing past the meter terminal housing while permitting the passage of electrical conductors between the meter and the devices in said casing through an opening in the adapter plate which forms one wall of the casing in the usual manner.

It will be noted that the feet for attaching the casing and the plate are both detachable from these parts and that at least one of these feet is adjustable in length so that the plate 15 may be brought into a vertical plane, and that the plate and casing may be turned slightly in this vertical plane to bring the meter in substantially its proper position, slight adjustments of the meter being also permitted by means of the slots 31 in the plate through which its fastenings pass. The casing and the meter supporting plate are attachable to the wall as a unit and to this unit may be secured a meter with its terminal chamber correctly positioned registering with the opening of the adapter plate forming one wall of the casing, any one of a variety of meters of different shapes and sizes being capable of assembly with the other parts in this manner.

As the meter is supported directly by a metal plate, which in turn is fixed directly to a metal casing, a ground connection to any of these parts grounds the meter frame. Such a connection for the casing is indicated at 40 in Figure 2.

Having thus described an embodiment of this invention it should be evident that various changes and modifications may be made therein without departing from its spirit or scope as defined by the appended claims.

I claim:

1. A meter support comprising a plate having meter fastener receiving openings adjacent one end thereof and a slot adjacent to the opposite end, said plate having a pair of spaced slits, the material therebetween being rearwardly offset from the plane of said plate to form an integral loop, and a strip passed between said loop and the rear face of said plate and bridging said slot, said strip being constructed to receive a meter fastener extending from the forward face of said plate through said slot.

2. In combination, a box like casing for the enclosure of meter protection devices, and having an opening in its upper wall for registry with the terminal chamber of a meter to permit the passage of electrical conductors between said meter and the devices in said casing, a plate to which said casing is removably secured, said plate having rearwardly directed marginal stiffening flanges and presenting an unobstructed front face, said plate having openings to receive meter fastening devices and a vertically arranged slot, a member, and means for holding said member vertically slidable relative to said plate at said slot, said member being formed to receive through said slot a meter fastening device at the upper portion of a meter, whereby said upper portion of the meter may be engaged with said member when in its lowered position with said meter inclined from the vertical whereupon said meter may be turned into vertical position raising said member and then lowered so that its terminal chamber may be brought into registry with said wall and prevent access to the interior of said casing therewith.

3. A meter support comprising a plate having a slot therein, a member having means to receive a meter fastening extending through said slot, and means independent of said meter fastening for movably holding said member against said plate while permitting said fastening to be moved in said slot.

4. A meter support comprising a plate having a slot therein, a member, means for adjustably holding said member against the rear face of said plate back of said slot, and meter securing means extending through said slot and engaging said member and by the tightening of which said member is held fixed to said plate.

5. A meter support comprising a plate having a slot therethrough, a member, means for holding said member against turning on the rear face of said plate but permitting sliding of said member lengthwise of said slot, and a threaded securing member extending through said slot and engaging said member.

In testimony whereof I have affixed my
signature.

GRANVILLE E. PALMER.
